UNITED STATES PATENT OFFICE.

FRANKLIN POWERS HAWKINS, OF PLANO, ALABAMA.

STEAM-ENGINE.

SPECIFICATION forming part of Letters Patent No. 380,110, dated March 27, 1888.

Application filed October 24, 1887. Serial No. 253,231. (No model.)

To all whom it may concern:

Be it known that I, FRANKLIN POWERS HAWKINS, a citizen of the United States, residing at Plano, in the county of Cherokee and State of Alabama, have invented new and useful Improvements in Steam-Engines, of which the following is a specification.

My invention relates to improvements in steam-engines; and it has for its objects to provide a cross-head for connection to the outer end of the piston-rod, which will accurately guide the latter in a straight line parallel with the motion of the piston-head and prevent all cramping and unnecessary friction.

With this object in view my invention consists in certain details of construction, herein-after more fully described in connection with the drawings, and specifically pointed out in the claims.

In the accompanying drawings, wherein similar letters of reference indicate corresponding parts in the several views—

Figure 1 is a side view of a portion of an engine embodying my improvements. Fig. 2 is a longitudinal section of the same. Fig. 3 is a top plan view.

Referring by letter to the drawings, A designates the bed of the engine, at one end of which is mounted the main shaft B, carrying the driving or fly wheel C, and the small wheel D, to which the eccentric E is attached.

G designates the cylinder, H designates the piston operating therein, and I designates the piston-rod, secured to the piston and passing through the head of the cylinder.

K designates a cross-head on the outer end of the piston-rod, provided at the front end with the forwardly-extending ears or lugs L L, between which is pivoted the rear end of the connecting-rod M, which is attached at the front end to the wheel D. The rear end of the head-block is provided with a recess, k, in which is mounted the end of the piston-rod, and a removable pin, i, is passed through the head-block and the end of the piston-rod to secure the latter in place. The sides of the said cross-head are provided with the laterally-extending wings or projections N N, which slide, respectively, on the upper and lower sides of the guide bars or ribs O O, which are arranged horizontally on opposite sides of

the block K. All tendency to lateral play of the piston-rod is thus avoided.

P designates the steam-chest disposed over the cylinder and having the ports Q Q leading to the opposite ends of the cylinder and the exhaust-openings R R, said ports and exhaust-openings being arranged near the ends of the steam-chest.

S designates the steam-supply pipe, which delivers steam into the chest at the center thereof.

T designates the valve-stem, which is threaded for a considerable distance within the steam-chest, and on the said stem are screwed the valves or valve-heads U U, which fit tightly in the steam-chest and are arranged at the same distance apart as the ports Q Q. It will be seen that the distance between the valve-heads is adjustable, owing to the fact that they are screwed on a threaded stem. It will also be observed that the valve-heads are on opposite sides of the supply-pipe, as before indicated.

V designates a standard secured to the bed of the engine, in which is formed a bearing or opening, W, to receive the outer end of the valve-stem. The motion of the valve-stem is thus guided and held from lateral play.

X designates the eccentric-rod, which is attached at the end to the valve-stem between the steam-chest and the standard V.

The operation of the invention is as follows: The steam is admitted through the supply-pipe to the space between the valve-heads, (the pressure upon the said heads being, as before mentioned, equal and in opposite directions,) and it passes through one of the ports to the cylinder on the left side of the piston, thereby moving the same to the right, as shown by the arrow in Fig. 2. The main shaft is thus rotated, causing the eccentric to operate the rod X, which is connected to the valve-stem. As the piston arrives at the end of the stroke, the ports at one end of the steam-chest are closed and those at the other end are opened, thereby causing the piston to start on the return-motion.

It will be seen that as the steam-port at one end of the steam-chest is opened into the space between the valve-heads the port at the other end of the chest is opened into the space be-

- yond the valve-head, thus allowing the steam which is ahead of the piston to pass through the port and escape through the exhaust-opening, which is adjacent to the port and also communicates with the space beyond the valve-head. This is in fact a balanced valve, in which the power necessary to operate it need only be sufficient to overcome the friction between the same and the sides of the chest. The pressure of the steam as it enters the chest is in all directions equal upon the sides of the chest and upon the inner sides of the valve-heads, and consequently, as the said valve-heads are both attached to the same stem, and therefore simultaneously movable in the same direction, the pressure in any one direction upon the valve is perfectly balanced and neutralized by an equal pressure in the opposite direction.
- Having thus described my invention, I claim as new and desire to secure by Letters Patent—
1. The combination, with the cylinder, and the piston-rod having the piston-head attached thereto within the cylinder, of the parallel guide-ribs O O on the bed of the engine, the

cross-head attached to the end of the piston-rod and having the lateral wings or projections N N, engaging the said guide-ribs, and the forward-extending ears L L, and the connecting-rod mounted between the said ears 30 and connected to the driving-shaft of the engine, substantially as and for the purpose specified.

2. The combination of the guide-ribs O O on the bed of the engine, the cross-head having the recess k in its rear end, the wings or projections on the sides of the cross-head engaging and sliding on the said guide-ribs, the connecting-rod connected at one end to the cross-head, the piston-rod arranged in the recess k, and the removable pin i, passing through the cross-head and the piston-rod, substantially as and for the purpose specified.

In testimony that I claim the foregoing as my own I have hereto affixed my signature in presence of two witnesses.

FRANKLIN POWERS HAWKINS.
